Atty.

UNITED STATES PATENT OFFICE.

ARLINGTON MOORE, OF BOSTON, MASSACHUSETTS.

PAPER DISH.

Application filed March 23, 1921. Serial No. 454,772.

The present invention relates to paper dishes, that is, to dishes made of any suitable fibrous stock, whether paper or resembling paper, and particularly to such a dish having a re-enforced rim. The dish may be circular, polygonal, or any suitable form, molded or formed in any suitable way. The paper stock may be single or multiple ply with or without incorporating a binder, and the dish may be coated with paraffin or otherwise treated to resist moisture and to withstand washing.

The dish, which may consist of one piece of stock, has a rim re-enforced to give strength and rigidity thereto. The rim, which is preferably triple-enforced, is formed from a continuation of the stock of the dish folded in overlying portions and where triple-enforced, into three overlying portions. The inner surface of the rim is preferably made to lie in uninterrupted conformity with the interior surface of the dish. Irrespective, however, of the continuity of the inner rim and dish surfaces, but preferably embodying this construction, the dish may have an upturned side wall, the upper portion of which is recessed, and the folds of stock may be anchored in said recess. Furthermore, the rim may be highly compressed and practically solidified, in which case the folds thereof are rigidly set to permanent gage dimensions. So formed and treated, the rim provides a substantial reinforcement for the dish against deformation in handling or in use. Where the rim is triple-enforced, the folds of stock may consist of a base portion, a reversely extending intermediate portion, and an enclosed terminal portion, the inner surface of the intermediate portion lying in uninterrupted conformity with the interior surface of the dish. In the specific embodiment described hereinafter, the base and intermediate portions are joined by means of a section of stock lying flat over the peripheral edge of the terminal portion to form a flat edge for the dish, thus facilitating the handling thereof.

Irrespective of the manner in which the rim of the dish is re-enforced, the invention comprehends as another of its parts, a paper dish having an upturned side wall and a re-enforced rim formed from a continuation of the stock of the side wall folded into overlying portions, the bottom of the dish having an annular depression which serves as

a stand for the dish to keep the bottom thereof out of contact with wet or damp surfaces upon which the dish might be placed. Preferably the bottom of the dish is slightly concaved outwardly to provide against warping and to increase the depth of the dish, and the annular depression is situated adjacent the upturned side wall to provide a stand of sufficient diameter to firmly support the dish when in use. Preferably one side of the annular depression lies in uninterrupted conformity with the upturned side wall so that the latter has a rounded section of stock joining it with the base to support it in the upturned or inclined position. The connecting section thus formed provides a stronger support for the side wall in a position inclined to the bottom than would be provided were the connection a corner or sharp edge.

Whether or not the dish is provided with an annular depression to serve as a stand therefor, but preferably so, the invention comprehends as still another of its parts, a one piece paper dish having a rim formed from a continuation of the stock thereof which is convoluted, preferably outwardly of said dish, to form a re-enforced rim or bead. Where the bead is highly compressed and practically solidified under great pressure the convolutions of stock are rigidly set to permanent gage dimensions and the rim re-enforces the dish against deformation under pressure in handling. The bottom of the dish may have an annular depression to serve as a stand therefor, one side of which preferably lies in uninterrupted conformity with the upturned side wall to provide a rounded connecting section between it and the bottom of the dish.

In the accompanying drawings illustrating the preferred embodiment of the invention in application, as an example, to a dish of single-ply stock,

Fig. 1 is a view in elevation of the dish partly in section and partly in full view; and Fig. 2 is a plan view of the dish shown in Fig. 1.

In the embodiment illustrated in Fig. 1, the dish has a bottom 1 slightly concaved outwardly, an upturned side wall 2, and a re-enforced rim 3. The rim 3 is formed from a continuation of the stock composing the dish and comprises a base portion 4, an intermediate portion 5, a section 6 joining the base and intermediate portions, and a

terminal portion 7 enclosed between the base and intermediate portions. The joining section 6 lies flat over the raw edge of the terminal portion 7, so that said edge is concealed, and is also protected from moisture, which might otherwise have access thereto either from without the dish, when it is placed in water to be washed, or through capillary attraction from its contents. The inner surface of the rim lies in uninterrupted conformity with the inside surface of the dish. Thus while the inner surface of the rim is made to constitute part of the interior surface of the dish and thereby to increase the depth thereof, the interior surface is smooth and unbroken. The bottom of the dish has an annular depression 9 adjacent the upturned side wall 2 which provides not only a rounded connecting section between the latter and the bottom of the dish, but also a stand 10 for raising the bottom above the level of the surface upon which the dish is placed.

Furthermore, the provision of the rounded connection is of importance for the reason that any strain on the side wall which is communicated to the bottom will not be concentrated at any one point between the side and bottom, but will be distributed throughout the entire curved portion, so that, while this portion may yield, under strain, it will be perfectly resilient and will always return to the form in which it was molded. As a result, the sides of the dish will not become distorted under ordinary conditions of use.

In the manufacture of the dish the resiliency and permanency of the curved connection portion or annular depression 9 is greatly increased during the molding operation, by so forming the molds or dies that the pressure to which this portion 9 is subjected, will be greatly in excess of that applied to the side and bottom, thereby causing this portion to be highly solidified.

The formation of the bottom 1 slightly concave is important in that this construction also assists in preventing deformation in use much more effectively than if it were flat.

The folds of stock composing the rim are subjected, in forming, to a pressure preferably of about 4000 to 6000 pounds per square inch, under which pressure the parts become highly compressed and practically solidified and are rigidly set to permanent gage dimensions.

Having thus described my invention, what I claim is:

60 1. As a new article of manufacture, a paper dish formed from an integral paper disk, an upturned flaring outer rim having a recessed upper portion, and a multi-reenforced marginal portion of said rim formed from a continuation of the stock thereof folded into

three overlying portions, said folds being anchored in said recess.

2. As a new article of manufacture, a paper dish formed from an integral paper disk, and comprising an upturned flaring outer rim having a recessed upper portion, and a multi-reenforced marginal portion of said rim formed from a continuation of the stock thereof folded into three overlying portions, said folds being anchored in said recess 70 and the inner surface of said reenforced marginal portion lying in uninterrupted conformity with the interior surface of the rim. 75

3. As a new article of manufacture, a paper dish formed from an integral paper disk, and comprising an upturned flaring outer rim having a recessed upper portion, and a highly compressed and practically solidified multi-reenforced marginal portion 85 of said rim formed from a continuation of the stock thereof folded into three overlying rigidly-set portions, said overlying portions being located in said recessed upper portion. 90

4. As a new article of manufacture, a paper dish formed from an integral paper disk, and comprising a multi-reenforced flaring outer rim formed from a continuation of the stock thereof and comprising a base portion, a reversely extending intermediate portion, and an enclosed terminal portion, the inner surface of said intermediate portion lying in uninterrupted conformity with the interior surface of the dish. 95

5. As a new article of manufacture, a paper dish formed from an integral paper disk, and comprising a multi-reenforced flaring outer rim formed from a continuation of the stock thereof and comprising a base portion, a reversely extending intermediate portion, a section joining said base and intermediate portions, and a terminal portion enclosed between said base and intermediate portions, said joining section lying flat over the peripheral edge of said terminal portion 100 to form a flat edge for the dish and the inner surface of said intermediate portion lying in uninterrupted conformity with the interior surface of the dish. 105

6. As a new article of manufacture, a paper dish formed from an integral paper disk, and comprising an upturned flaring outer rim and a reenforced marginal portion of said rim formed from a continuation of the stock thereof folded into overlying portions, the bottom of said dish being concaved outwardly and having therein an annular depression adjacent the upturned side wall. 115

7. As a new article of manufacture, a paper dish formed from an integral paper disk, and comprising an upturned outer flaring rim, a reenforced marginal portion of said rim formed from a continuation of the stock thereof folded into overlying portions, 120 130

the bottom of said dish being concaved outwardly and having an annular depression therein one side of which lies in uninterrupted conformity with said upturned side 5 wall.

8. A circular paper dish formed from a paper disk compressed and moulded to form a paper dish having an annular depressed portion connecting the side and bottom 10 thereof, said annular depressed portion being more highly solidified by compression than the adjacent portions of the dish.

9. A circular paper dish formed from a circular paper disk comprising an outer flar- 15 ing rim portion terminating in a multi-
reinforced margin in which the raw edge of the paper is imbedded between folds there-
of, a bottom portion and a connecting portion joining the rim portion and the bottom portion, said connecting portion being 20
curved downwardly from its junction with the rim portion and then upwardly and joining the bottom portion at an angle, and com-
prising a part more highly solidified by compression than the adjacent portions of 25
the disk.

In testimony whereof I affix my signature.

ARLINGTON MOORE.
